[57] CLAIM

The ornamental design for a pulse receiver, as shown.

DESCRIPTION

FIG. 1 is a top plan view of a pulse receiver, showing our new design;

FIG. 2 is a side elevational view thereof;

FIG. 3 is a bottom plan view thereof;

FIG. 4 is an elevational view of the side opposite that shown in FIG. 2;

FIG. 5 is a left end elevational view thereof;

FIG. 6 is a right end elevational view thereof.
